UNITED STATES PATENT OFFICE.

RUSSELL L. O'KEEFFE, OF SAN FRANCISCO, CALIFORNIA, ASSIGNOR TO HALE BROS., INC., OF SAN FRANCISCO, CALIFORNIA, A CORPORATION OF CALIFORNIA.

DESIGN FOR A TOWELING FABRIC.

Application filed July 13, 1925. Serial No. 14,068. Term of patent 14 years.

To all whom it may concern:

Be it known that I, RUSSELL L. O'KEEFFE, a citizen of the United States, residing at the city and county of San Francisco, State of California, have invented a new, original, and ornamental Design for a Toweling Fabric, of which the following is a specification, reference being had to the accompanying drawing, forming a representative part thereof.

The drawing is a face view of a piece of the toweling fabric constituting my new design.

I claim:

The ornamental design for a toweling fabric, substantially as shown and described.

RUSSELL L. O'KEEFFE.
